US00D594863S

(12) **United States Design Patent**
Ichise et al.

(10) **Patent No.:** US D594,863 S
(45) **Date of Patent:** ** Jun. 23, 2009

(54) **MOBILE INFORMATION TERMINAL**

D550,710 S 9/2007 Ichinose
D554,098 S 10/2007 Lee

(75) Inventors: **Kentaro Ichise**, Tokyo (JP); **Taihei Miyaji**, Tokyo (JP)

(73) Assignee: **Kabushiki Kaisha Toshiba**, Tokyo (JP)

FIG. 1 is a bottom, front and left side perspective view a mobile information terminal showing our new design,

FIG. 2 is a bottom, front and left side perspective view with a keyboard in an in use position;

FIG. 3 is a front elevational view of the mobile information terminal of FIG. 1,

FIG. 4 is a rear elevational view thereof,

FIG. 5 is a left side elevational view thereof,

FIG. 6 is a right side elevational view thereof,

FIG. 7 is a top plan view thereof,

FIG. 8 is a bottom plan view thereof,

FIG. 9 is a reduced front elevational view with the keyboard in an in use position; and,

FIG. 10 is a reduced bottom plan view with the keyboard in an in use position.
